US00D700516S

(12) **United States Design Patent** (10) **Patent No.:** **US D700,516 S**
Adams et al. (45) **Date of Patent:** **** Mar. 4, 2014**

(54) **OVERCAP**

(71) Applicants: **Mary Beth Adams**, Antioch, IL (US);
Daniel A. Andersen, Burlington, IL (US); **Jeffrey J. Christianson**, Oak Creek, WI (US); **Matthew Grossman**, Austin, TX (US); **Kit R. Morris**, Austin, TX (US); **Han Xin**, Shanghai (CN)

(72) Inventors: **Mary Beth Adams**, Antioch, IL (US);
Daniel A. Andersen, Burlington, IL (US); **Jeffrey J. Christianson**, Oak Creek, WI (US); **Matthew Grossman**, Austin, TX (US); **Kit R. Morris**, Austin, TX (US); **Han Xin**, Shanghai (CN)

(73) Assignee: **S.C. Johnson & Son, Inc.**, Racine, WI (US)

(**) Term: **14 Years**

(21) Appl. No.: **29/470,812**

(22) Filed: **Oct. 25, 2013**

Related U.S. Application Data

(62) Division of application No. 29/428,122, filed on Jul. 26, 2012, which is a division of application No. 29/397,465, filed on Jul. 15, 2011, now Pat. No. Des. 666,491.

Primary Examiner — Robert M Spear

CLAIM

The ornamental design for an overcap, as shown and described.

DESCRIPTION

FIG. 1 is an isometric view of a top, front, and left side of an ornamental design for an overcap;

FIG. 2 is a front elevational view of the overcap of FIG. 1;

FIG. 3 is a rear elevational view of the overcap of FIG. 1;

FIG. 4 is a left side elevational view of the overcap of FIG. 1;

FIG. 5 is a right side elevational view of the overcap of FIG. 1; and,

FIG. 6 is a top plan view of the overcap of FIG. 1.

The broken lines are for the purpose of illustrating environmental structure and form no part of the claimed design. Further, the bottom view forms no part of the claimed design.

1 Claim, 3 Drawing Sheets
